PENDANT

Harold Antoine, Jr., 8449 Fresno Court,
Cool Valley, Mo. 63121

Filed Oct. 16, 1972, Ser. No. 298,437

Term of patent 14 years

Int. Cl. D11—01

U.S. Cl. D45—15

FIG. 2

FIG. 1

FIG. 3

FIG. 5

FIG. 4

FIG. 1 is a front elevational view of a pendant showing my new design;

FIG. 2 is a top edge view thereof;

FIG. 3 is a right side edge view, the left side being a mirror image thereof;

FIG. 4 is a bottom edge view; and

FIG. 5 is a cross-sectional view taken on line 5—5 of FIG. 1.

The rear elevational view of the pendant is substantially the same as FIG. 1.

I claim:

The ornamental design for a pendant, substantially as shown and described.
